ELECTRIC SWITCH

Erik Oskar Helge Hansson, Stockholm, Sweden,
assignor to Electrolux Corporation, Dover, Del.,
a corporation of Delaware

Application June 5, 1937, Serial No. 146,619

2 Claims. (Cl. 200—159)

My invention relates to an electric switch and more particularly to a switch adapted especially for operation by the foot of the operator. One of the objects of my invention is to provide a switch of this type including a housing in which is mounted standard switch mechanism. Preferably, the housing of the switch in accordance with my invention comprises two parts, to one of which may be secured the aforesaid switch mechanism, the other part of the housing serving merely to provide an enclosure along with the first mentioned part.

Still another object of my invention is to provide a switch which has an actuating member arranged to be forced inwardly, especially by foot pressure, to actuate the switch mechanism, the construction being such that excessive foot pressure cannot be transmitted to the switch mechanism, but will be taken entirely by a stationary part or parts which may be readily constructed of sufficient strength to withstand such pressure without injury.

Further objects and advantages of my invention will be apparent from the following description considered in connection with the accompanying drawing which forms a part of the specification and of which:

Fig. 1 is a side view, partially in cross-section, showing my improved switch with one of the parts of the housing removed;

Fig. 2 is a cross-sectional view taken on the line 2—2 of Fig. 1;

Fig. 3 is a cross-sectional view taken on the line 3—3 of Fig. 1;

Fig. 4 is a cross-sectional view, on a reduced scale, taken on the line 4—4 of Fig. 1; and

Fig. 5 is an elevational view, on a reduced scale, of the portion of the housing which is not shown in Fig. 1.

Referring to the drawing, reference character 10 designates generally a housing which includes separable parts 11 and 12. Part 11 has a face 13 which mates with a similar face 14 formed on part 12. The two parts are secured together by a plurality of bolts 15 which pass therethrough.

The housing as a whole is formed with two interior communicating recesses 16 and 17. Both of these recesses are formed in both of the parts 11 and 12 of the housing. Mounted in recess 16 is a switch mechanism 18 which includes a substantially rectangular frame made up of an L-shape piece of insulating material 19 and an L-shape piece of metal 20. Insulating material 19 may be laminated, as shown, and piece 20 is U-shaped in cross-section, as is seen in Fig. 4, so as to embrace both sides of piece 19. Pieces 19 and 20 are secured together by means of bolts 21 extending therethrough. Bolts 21 also extend through part 11 of the housing, as shown in Fig.

4, so as to securely fasten the frame in the recess. While separate bolts might be employed to secure the frame to the housing, certain advantages are obtained from the construction shown. It will be noted that bolts 21 engage diagonally opposite corners of the rectangular frame and hence the force exerted by the bolts is evenly distributed over the frame. If separate bolts were used, they would have to be located elsewhere. As it is desirable that the bolts engage the metal part 10 10, it will be seen that no other location would give as equal force distribution.

Secured to one side of frame part 19 adjacent to the angle thereof, is a switch contact member 22. A similar contact member 23 is secured to 15 the other side of the frame part 19. The horizontal leg of part 19 is formed as a track 24 on which runs a metallic flanged roller 25 which constitutes the member for making and breaking the circuit between the members 22 and 23. In 20 the position of the switch shown in Fig. 1, roller 25 is out of contact with members 22 and 23 and consequently the switch is open. However, when the roller travels to the other end of track 24 it contacts both members 22 and 23, thereby 25 closing the circuit between them.

Member 25 is held against the track by means of a member 26, preferably made of insulating material which constitutes one arm of a toggle mechanism, the other arm of which is designated 30 by reference character 27 and is pivoted in frame part 20 by a pin 28. One end of arm 27 is formed with a pin 29 which slides in a slot 30 formed in arm 26. A spring 31 is compressed between a shoulder 32 formed on arm 26 and the pin 29. 35 Spring 31 tends to maintain the toggle mechanism in one or the other of its extreme positions.

The switch mechanism 18, including the rectangular frame 19, 20, the contacts 22 and 23 and the toggle mechanism 25—32 is of standard 40 design, and forms per se no part of my invention.

Connected to or integral with switch contact 22 is an arm 35 which extends downwardly through an opening 36 formed in part 12 of the housing. The lower end of arm 35 is provided with a binding screw 37 to which may be attached an electric conductor in the form of a wire. Attached to or integral with switch contact 23 is an arm 38 which extends around the edge of frame part 19 and hence upwardly along this 45 edge. Secured to the upper end of arm 38 is a contact prong 39 which extends to the exterior of housing 10 through an opening 40 formed partly in both halves of the housing.

The lower part of housing 10 is formed with a 55 recess 41 in which is secured an arm 42 by means of a bolt 43 extending through the wall of the housing. To one end of this arm is secured a contact prong 44 which extends through an opening 45 to the exterior of the switch housing; this 60

opening likewise being formed in both parts of the housing. The other end of arm 42 extends to a notch 46 formed in the bottom of part 11 of the housing and is there provided with a binding screw 47 similar to binding screw 37 but being located on the opposite side of the center line of the housing.

The recess 17 formed in the upper portion of housing parts 11 and 12 is generally cylindrical in shape and is provided with diametrically opposed rectangular grooves 50. Reciprocably mounted in recess 17 is a hollow button 51 formed with diametrically opposed projections 52 which are adapted to slide within grooves 50. Thus, rotation of the button is prevented and, inasmuch as the grooves 50 are closed at the top, removal of the button is also prevented. The switch housing is formed with an opening 53 through which the upper part of button 51 projects so as to be accessible for operation by the foot.

The upper part of the interior of button 51 is formed with a groove 54 within which is received a pin 55. Pin 55 extends through an opening 25 formed in the upper end of an arm 56, this upper end being received in a groove 57 in the button which extends at right angles to groove 54. By virtue of its being received in groove 57 axial displacement of arm 56 along pin 55 is prevented. Arm 56 is formed with a pair of ears 58 extending at right angles to the main portion of the arm. A ring 59 is forced against ears 58 by means of a spring 60, the lower end of which abuts against the bottom of recess 17. Spring 35 60, by forcing ring 59 against both of the ears 58 not only tends to maintain the arm 56 in a vertical position as shown in Fig. 1, but it also tends to hold button 51 in projected position. Also, the spring holds pin 55 within groove 54.

40 With the parts in the position shown in Fig. 1, downward movement of button 51 causes the lower end of arm 56 to press against the bottom of a recess 64 formed in the upper end of arm 27. In order to reach the bottom of the recess 45 it is necessary for arm 56 to pivot slightly around pin 55, which it may do by displacement of one side of ring 59 against the force of spring 60. Continued downward movement of the button 51 and the arm 56 carried thereby, tends to rotate 50 arm 51 in a clock-wise direction (as viewed in Fig. 1) about pivot 28 and against the force exerted by spring 31. Such rotation of arm 27 tends to straighten out the toggle and after the arms 26 and 27 have passed their dead center 55 position, the spring 31 will continue the movement of the toggle and will cause the roller 25 to travel along the track 24 until it strikes the switch contacts 22 and 23. As above described, the circuit of the switch is now closed and contact prong 39 is now connected electrically with binding screw 37.

Due to the loose connection between arms 27 and 56, the spring 31 is able to snap the toggle mechanism to its extreme position, after the 60 mechanism has passed dead center, without regard to the speed of travel of arm 56.

Moreover, the parts are so proportioned that when button 51 strikes the bottom of recess 17, the lower end of arm 56 is spaced more or less 65 from the bottom of recess 64. Consequently, no matter how much force is applied to the upper end of the button, only sufficient force to actuate the toggle is transmitted to the toggle mechanism. The remaining force is transmitted directly to the switch housing, whereby the switch 70

mechanism is protected against injury resulting from the use of excessive force.

After the above described operation has been completed and the force relieved from button 51, spring 60 returns the button to its uppermost position and centers arm 56. The recess 65 on the other side of arm 26 is now underneath the lower end of arm 56 and the next reciprocation of button 51 will serve to return the parts to the position shown in Fig. 1.

Switch housing 10 is made of suitable rigid insulating material, such as "Bakelite." This housing may be enclosed within a shell 66 which may be secured to the device on which the switch is mounted. As shown, a screw 67 secures a portion of the shell 66 to a member 68 which is attached to housing 69 of, for instance, a vacuum cleaner.

It will be noted that no special means are required to secure button 51 within the housing 10. The button may be placed in the portion of the recess 17 which is formed in housing part 11 before the two parts are secured together and when the parts are secured together the button is retained within the now complete recess.

While I have described one more or less specific embodiment of my invention it is to be understood that this has been done for the purpose of illustration only, as required by the patent statutes, and that the scope of my invention 30 is not to be limited thereby, but is to be determined by the appended claims when viewed in the light of the prior art.

What I claim is:

1. An electric switch comprising a housing having two interior communicating recesses, switch mechanism secured in one of said recesses including a frame and a switch arm pivotally mounted on said frame, a hollow button located in the other of said recesses and extending to the exterior of said housing, an arm having a pair of ears loosely carried in a groove in said button and adapted to engage said switch arm upon downward movement of said button, a pin passing through said last-named arm and loosely carried in a groove in said button extending at right angles to said arm, a washer engaging the ears of said last-named arm and said pin, a wall between the two recesses of said housing, and a spring engaging said washer and said wall urging said button upwardly and holding said last-named arm in line with the axis of said button.

2. An electric switch comprising a housing having two interior communicating recesses, switch mechanism secured in one of said recesses including a frame and a switch arm pivotally mounted on said frame, a hollow button located in the other of said recesses and extending to the exterior of said housing, projections from said button engaging in notches 60 in said housing and stopping upward movement of said button, an arm having a pair of ears loosely carried in a groove in said button and adapted to engage said switch arm upon downward movement of said button, a pin passing 65 through said last-named arm and loosely carried in a groove in said button extending at right angles to said arm, a washer engaging the ears of said last-named arm and said pin, a wall located between the two recesses of said housing, and a spring engaging said washer and said wall biasing said last-named arm to a vertical position in line with the axis of said button and urging said button upwardly.
